UNITED STATES PATENT OFFICE.

ALINE PHILLIPS, OF SEATTLE, WASHINGTON.

DESIGN FOR A SPOON.

SPECIFICATION forming part of Design No. 34,526, dated May 21, 1901.

Application filed April 5, 1901. Serial No. 54,545. Term of patent 3½ years.

To all whom it may concern:

Be it known that I, ALINE PHILLIPS, a citizen of the United States, residing at Seattle, in the county of King and State of Washington, have invented a new and original Design for a Spoon, of which the following is a specification, reference being had therein to the accompanying drawings.

My invention relates to a novel design for spoons, the object being the production of a spoon which will be of attractive and beautiful appearance and prove a useful article as well as a souvenir.

With the above-stated object in view my invention consists of the spoon shown in the accompanying drawings and disclosed herein.

Figure 1 represents a front or face view of the spoon, and Fig. 2 represents a view of the back or rear of the spoon.

The handle of my spoon has its edge formed with the broken lines A to give an Arctic appearance to the handle, and upon the handle is the representation B of a pack-sled drawn by dogs, the sled being at the end of the spoon and the team of dogs extending from the sled into the bowl C of the spoon, and upon the bowl is the pictorial representation D of a harbor, with a man D' at work upon the shore, and a boat, with men E mining in the harbor.

I claim—

The design for a spoon herein shown and described.

In testimony whereof I affix my signature in presence of two witnesses.

ALINE PHILLIPS.
